Application February 8, 1956, Serial No. 564,203

11 Claims. (Cl. 233—14)

This invention relates to centrifugal separators of the type in which the material to be separated is fed into the centrifugal bowl through a hollow axial spindle rotatable with the bowl. The invention has particular reference to an improved centrifuge of this type having means for feeding an auxiliary liquid into the bowl apart from the main feed and in such a manner that relatively heavy material separated from the feed is continuously flushed from the bowl by the auxiliary liquid without impairing the separating operation.

In the use of centrifuges for refining vegetable oils, for example, it is common practice to feed a mixture of the oil and lye or other refining agent to the centrifuge, where the soap formed by the reaction of the lye with the free fatty acids in the oil is separated as a heavier component in the separating chamber of the centrifugal bowl. The oil and the soap should, of course, be discharged separately and continuously from the bowl as lighter and heavier components, respectively; but this presents difficulties in the case of the soap due to its relatively high viscosity and its tendency to accumulate in the outer peripheral part of the bowl. It has been proposed heretofore to feed an auxiliary liquid, such as water, into the bowl during the separating operation, this liquid having a specific gravity such that it accompanies the heavier separated component and acts to flush this component from the outer part of the bowl. However, this practice, too, has its difficulties, such as creation of an emulsion of the auxiliary liquid and the lighter component, which makes the latter difficult to separate, or impairment of the separating operation by the flow of the auxiliary liquid through the bowl.

The present invention has for its principal object the provision of a centrifuge having improved means for delivering an auxiliary liquid to the bowl for flushing out the separated heavier component, which is simple in construction, and which overcomes the above-noted difficulties.

For illustrative purposes, the new centrifuge will be described in connection with the centrifugal separation of soap from vegetable oils, although it will be understood that the invention is not limited to this use.

The centrifugal separator of the present invention is of the type having a hollow axial spindle on which the centrifugal bowl is mounted and which rotates with the bowl, the spindle being rotatably mounted in a frame and having its hollow interior communicating with the bowl at one end and with a stationary inlet at the other end, whereby the spindle forms a passage for the feed material to be separated.

According to the invention, a tube is secured in the hollow spindle and contains a central passage for the main feed to the bowl (the mixture of oil and refining agent in the example previously mentioned). This tube forms with the spindle an outer passage which is separated from the central passage and which serves for introducing the auxiliary liquid into the bowl. The

2

frame of the centrifuge has two inlets, one for the main feed and the other for the auxiliary liquid; and sealed flow connections are provided from these inlets to the central and outer passages, respectively, in the hollow spindle. These passages extend into the centrifugal bowl, and the latter contains means forming a first generally radial passage leading from the outer passage of the spindle and terminating at the outer peripheral portion of the separating chamber in the bowl. Such means also form a second generally radial passage leading from the central passage of the spindle and terminating in the separating chamber at a region located substantially inward from the peripheral portion. The bowl has an outlet for discharge of a separated lighter component from the inner portion of the separating chamber, the bowl also having a heavier component discharge passage leading from the outer peripheral portion of the separating chamber.

With this arrangement, the auxiliary liquid is led separately from the outer passage of the hollow spindle to the peripheral portion of the bowl, so that this liquid does not mix with the lighter component of the feed material entering the bowl from the central portion of the spindle. Thus, the auxiliary liquid serves to dilute the soap and unreacted lye separated as a heavier component from the oil and to flush this heavier component from the peripheral part of the bowl through the heavier component discharge passage, without forming an emulsion with the oil or otherwise impairing the separating operation.

In the preferred form of the new centrifuge, the passage forming means in the bowl include a hollow member defining a second chamber in the bowl, the central passage of the spindle opening into the central portion of this second chamber and the latter having an opening in its outer peripheral portion through which the feed material passes into the main separating chamber of the bowl. The bottom of this hollow member is located above the bowl bottom and defines therewith a generally radial channel leading to the outer peripheral part of the main separating chamber, the auxiliary liquid being delivered into this channel through a lateral opening in the hollow spindle. Thus, the bottom of the hollow member forming the secondary chamber for the feed material in the bowl also serves to maintain the feed material separated from the auxiliary liquid as the latter passes to the outer portion of the separating chamber to flush away the separated heavier component.

These and other features of the invention will be better understood by reference to the accompanying drawing, in which:

Fig. 1 is a side elevational view, partly in section, of a preferred form of the new centrifuge, showing the bowl, the upper part of the hollow spindle and the sealed flow connections for leading the separated components to stationary discharge outlets;

Fig. 2 is a vertical sectional view of the lower part of the centrifuge illustrated in Fig. 1, showing the sealed flow connections from the stationary inlets to the lower ends of the passages in the hollow spindle;

Fig. 3 is an enlarged vertical sectional view of the upper part of the centrifuge, showing details of the sealed flow connections from the bowl outlets, and

Fig. 4 is a sectional view on line 4—4 in Fig. 2.

Referring to the drawings, the centrifuge as illustrated comprises a bowl shell 10 and a generally conical top 11 secured to the shell by a threaded clamping ring 12. Within the centrifugal bowl 10-12 is a main separating chamber containing a series of spaced conical discs 13. The main separation in the bowl takes place in the spaces between the conical discs 13, as will be readily apparent

to those skilled in the art. A hollow member 14 is located in the lower part of the bowl where it rests upon the bowl bottom 15. The hollow member 14 tapers upwardly from the bowl bottom and has a bottom 14a closely surrounding a central nave 16 which is integral with the bowl bottom and extends upwardly therefrom. At its lower portion, the nave 16 has an annular external shoulder 16a on which the bottom 14a of the hollow member rests.

The hollow member 14 serves as a carrier for the discs 13, the lowest disc in the stack resting on the conical surface of the hollow member. A center post 14b extends upwardly from the hollow member 14 and through central openings in the discs 13. At their inner edges the discs 13 have clearances with the center post 14b to provide for upward passage of the lighter component separated between the discs, as will be described in greater detail presently. When the bowl top 11 is removed from the shell 10, the discs 13 and the discs carrier 14-14b can be lifted as a unit from the shell.

The centrifugal bowl 10-12 is rotatable on a hollow axial spindle 18. This spindle has a tapered upper end portion 18a which fits into the correspondingly tapered interior of the nave 16, so that the bowl is supported on the spindle by the nave. A hollow nut 19 is screwed on the upper end of the tapered spindle portion 18a and engages the upper end of the nave to prevent lifting of the bowl from the spindle. The spindle 18 is mounted for rotation in a stationary frame, part of which is shown at 21 (Fig. 2). The mounting of the spindle in the frame may be effected by a lower bearing assembly 22 of conventional form and the usual upper bearing assembly (not shown). It will be understood that by means of these bearing assemblies, the bowl and spindle are supported in the frame for rotation about the axis of the spindle, the bearing assemblies permitting a limited amount of radial movement of the bowl during its rotation, as is conventional in the art. The bowl may be rotated by any suitable driving means, such as an electric motor (not shown) having a driving connection to the spindle.

At its lower end, the spindle 18 has an enlarged flange 23 threaded on the spindle below the bearing assembly 22, this flange forming a downwardly opening recess. Within the spindle is a tube 25, the lower end of which extends into the recess formed by flange 23. This tube has an external diameter somewhat less than the internal diameter of the hollow spindle, except at the upper portion 25a (Fig. 1) of the tube, where the latter fits closely into the spindle. The upper end of the tube 25 may be secured in any desired manner to the spindle, as by means of mating threads on the outside of the tube and on the inner wall of the hollow spindle. The lower end of the tube 25 is closely surrounded by a sealing collar 26 located within the flange 23 and having radial spokes 26a extending outwardly into engagement with the cylindrical inner wall of the flange. Therefore, the lower end of the tube 25 is held by the spoked collar 26 against lateral movement relative to the spindle 18, and the upper end of the tube is secured directly to the spindle to prevent lateral and longitudinal movement of the tube relative to the spindle. Thus, the tube 25 rotates with the spindle and forms therewith an annular outer passage 27 surrounding the central passage defined by the tube itself.

A stationary fitting 21a is removably mounted on the frame 21. This fitting has a main feed inlet 29 to which the mixture of vegetable oil and refining agent is delivered under pressure through a supply pipe. A passage 30 extends upward from the inlet 29 into an enlarged recess 31 in the fitting 21a. A tube 32 is secured at its lower end to the bottom of recess 31 and forms an upward extension of the passage 30. In the upper part of the tube 32 is a sealing collar 33 which fits closely in the tube and is slidable axially therein. The collar 33 is

urged upward against the sealing collar 26 by a compression spring 34 arranged within the lower part of tube 32.

A nipple 36 is threaded into the side wall of the stationary fitting 21a, and an auxiliary feed line 37 communicates through this nipple with the outer part of recess 31 surrounding the tube 32. The feed line 37 serves to deliver an auxiliary liquid, such as water, under pressure, to the recess 31. In the upper part of the recess 31 is an outer sealing collar 38 which fits closely against the cylindrical inner wall of the recess, this collar being slidable axially of the spindle 18. A compression spring 39 is seated on the bottom of recess 31 and urges the outer collar 38 upwardly against the lower end of the flange 23.

It will be apparent that the tube 32, the enlarged flange 23 and the collars 26-33-38 form sealed flow connections from the stationary inlets 29 and 36 to the central passage in the tube 25 and the annular passage 27, respectively. That is, the feed material flows upward from inlet 29 through passage 30, the interior of tube 32 and collar 33 to the central passage in tube 25 by way of the collar 26, and the auxiliary liquid flows upward from the outer part of recess 31 through the annular space between tube 32 and collar 38, and between the spokes 26a to the lower end of the annular passage 27. The inner collar 33, by virtue of its sealing contact with the tube 32 and opposed collar 26, seals the flow of the main feed from the flow of the auxiliary liquid. Similarly, the outer ring 38, by virtue of its sealing contact with flange 23 and the inner wall of recess 31, seals the flow of the auxiliary liquid from atmosphere. Any accidental leakage of the auxiliary liquid may be discharged from the interior of the fitting 21a by way of escape holes 21c. It will be apparent that the flange 23 and the collar 26 can slide laterally on the sealing collars 38 and 33, respectively, while maintaining the sealed flow connections, so as to accommodate the previously mentioned movements of the bowl during its rotation.

The lower ends of the spindle 18 and tube 25 are readily accessible by removing the fitting 21a from the frame 21. This permits the flange 23 to be unscrewed from the lower end of spindle 18, whereby the bowl 10-12 and spindle 18 can be lifted as a unit from the frame. Also, removal of the fitting 21a from the frame permits easy access to the sealing collars 26, 33 and 38 for inspection or replacement.

The feed material passes upwardly from the spindle tube 25 into the hollow nut 19, from which the feed material discharges outwardly through radial holes 19a in the nut and flows into the central upper portion of the secondary chamber in the hollow member 14. This secondary chamber may be provided with radial wings or vanes 14d for bringing the entering feed material up to the rotational speed of the bowl. In this secondary chamber, the feed material is subjected to a somewhat greater separating action than in the spindle tube 25, due to the greater diameter of the hollow member 14. At its lower portion, the hollow member 14 has holes 14c in the periphery of the member through which the feed material passes from the outer portion of the secondary chamber into the intermediate portion of the primary separating chamber containing the discs 13. It will be understood that the discs have holes aligned vertically with the holes 14c, whereby the feed material can pass directly into the separating spaces between the discs.

The spindle 18 and the nave 16 are provided with aligned radial holes 41 located just below the level of the bottom 14a of the hollow disc carrier 14. These holes extend from the upper end of the outer passage 27 in the spindle to a recess in the lower face of the bottom 14a of the hollow disc carrier, as shown in Fig. 1. Radial wings or vanes 42 are located in this recess and secured to the lower face of the bottom 14a. These wings form generally radial channels extending outwardly to radial

channels 42a formed in the bowl bottom 15. The latter channels extend under the lower edge of the periphery of the hollow member 14 and open into the main separating chamber under the outer edge portion of the lowermost disc 13, as shown in Fig. 1.

It will be apparent that the hollow member or disc carrier 14 constitutes a means in the bowl forming the generally radial passage leading from the central passage in the spindle tube 25 by way of the hollow nut 19 and the secondary chamber within the hollow member 14 and terminating at the holes 14c in the main separating chamber at a region located substantially inward from the outer peripheral portion of the latter chamber. The hollow member 14 in conjunction with the holes 41 and the bowl bottom 15 also constitutes a means forming a generally radial passage leading outward from the spindle passage 27 by way of the channels between the radial wings 42 and the channels 42a and terminating at the outer peripheral portion of the separating chamber below the discs. Thus, the auxiliary liquid is led from the outer passage 27 in the spindle through this generally radial passage, separately from the main feed, and flows under the lower or outer edge of the bottom disc 13 into the peripheral portion of the bowl.

Due to the centrifugal force generated in the revolving bowl, the feed material is separated between the discs 13 into oil as a lighter component and soap and unreacted lye as a heavier component. The separated oil is displaced inwardly between the discs and flows upwardly toward the top of the bowl through the clearance spaces between the center post 14b and the inner edges of the discs. From this central portion of the bowl, the oil flows into a central discharge passage 44 in the bowl neck by way of holes 45 leading into a recess in the upper portion of center post 14b; this recess opening upwardly into the discharge passage 44. The heavier component flows outwardly from the disc spaces into the peripheral portion of the main separating chamber, where it is joined by the flush water or auxiliary liquid introduced under the outer edge of the bottom disc 13. This liquid dilutes the heavier component and flushes it upwardly toward the top disc 46 which is of somewhat greater diameter than the discs 13. The diluted heavier component passes around the outer edge of the top disc 46 and upwardly and inwardly through a space 47 between the top disc 46 and bowl top 11. This space forms discharge passages for the heavier component leading to an annular outlet 48 in the bowl neck. The outlets 44 and 48 extend upwardly and through the bowl neck and are separated from each other by an annular part 49 of the neck.

Above the bowl 10-12 is a stationary fitting 51 having an outlet 52 for the lighter component and an outlet 53 for the heavier component. The outlets 52 and 53 have sealed flow connections with the bowl outlets 44 and 48, respectively. These flow connections may be arranged as disclosed in my copending application Serial No. 480,009, filed January 5, 1955. These flow connections comprise a stationary tube assembly 55 in the hollow fitting 51 forming an upward extension of the central outlet or discharge passage 44 in the bowl neck, this extension leading upward to the stationary outlet 52. Fitted closely in the lower portion of the tube assembly 55 is an inner sealing ring 56 which is slidable vertically in the tube assembly, this ring being spring-biased downwardly against the annular part 49 of the bowl around the outlet 44. An intermediate sealing ring 57 closely surrounds the tube assembly 55 at its lower portion and is spring biased downwardly against the outer portion of the annular part 49 of the bowl. An outer sealing ring 58 is closely surrounded by the inner wall of the fitting 51 and is spring biased downwardly against the outer annular part of the bowl neck around the heavier component outlet 48. The heavier component from the out-

let 48 passes upward between the sealing rings 57-58 and into the space surrounding the tube assembly 55, from which it discharges through the stationary outlet 53. It will be understood that the sealing rings 56-57-58 permit lateral or radial movements of the bowl while maintaining a sealed outlet path for the lighter and heavier separated components, as previously described.

The present invention provides a simple but highly effective arrangement, in a centrifuge of the hermetic type, for delivering both the main feed and an auxiliary liquid under pressure and apart from each other through the bowl spindle to the centrifugal bowl and leading the auxiliary liquid directly to the outer portion of the main separating chamber, where it joins the heavier separated component and flushes the latter from the bowl. The threaded connection between the upper end of the spindle 18 and its contained tube 25, together with the spoked collar 26a surrounding the lower end of this tube in the flange 23, constitute a simple means for positioning the tube in the spindle to form the annular outer passage 27, such means permitting the tube to be readily disassembled from the spindle. The hollow member 14 serves not only as a carrier for the discs 13 but also as a means coacting with the bowl parts 15-16 to form generally radial passages through which the main feed and the auxiliary liquid are led separately from the spindle tube 25 and the spindle passage 27 to the intermediate and outer portions, respectively, of the main separating chamber in the bowl.

30 I claim:

1. In a centrifugal separator having a centrifugal bowl provided with a separating chamber a hollow axial spindle secured to the bowl and rotatable therewith, and a frame rotatably supporting the spindle and having two stationary inlets, the combination of a tube secured in the hollow spindle and rotatable therewith, the tube containing a central passage and forming with the spindle an outer passage separate from said central passage, sealed flow connections from said stationary inlets to said passages, respectively, said passages extending into the bowl and means in the bowl forming a first generally radial passage leading from said outer passage and terminating at the outer peripheral portion of the separating chamber, said means also forming a second generally radial passage leading from said central passage and terminating in the separating chamber at a region located substantially inward from said peripheral portion, the bowl having an outlet for discharge of a separated lighter component from the inner portion of said chamber, the bowl also having a heavier component discharge passage leading from said peripheral portion of the separating chamber.

2. The combination according to claim 1, in which the frame also has two stationary outlets, the combination comprising also sealed flow connections from said bowl outlet and discharge passage to said stationary outlets, respectively.

3. The combination according to claim 1, in which said passage forming means include a hollow member defining a second chamber in the bowl, said central passage opening into the central portion of the second chamber, the hollow member having an opening in its outer peripheral portion, said opening and second chamber each forming part of said second generally radial passage.

4. The combination according to claim 1, in which the bottom of the bowl has a hollow nave extending into the bowl and receiving one end portion of the spindle, said first generally radial passage including generally radial holes in the spindle and nave.

5. The combination according to claim 1, in which the bottom of the bowl has a hollow nave extending into the bowl and receiving one end portion of the spindle, said first generally radial passage including generally radial holes in the spindle and nave, said central passage extending upward in the spindle above said holes, said

second generally radial passage being located above said first generally radial passage.

6. The combination according to claim 1, in which said passage forming means include a hollow member defining a second chamber in the bowl, said central passage opening into the central portion of the second chamber, the hollow member having an opening in its outer peripheral portion, said opening and second chamber each forming part of said second generally radial passage, said hollow member having a bottom located above the bowl bottom and defining therewith a generally radial channel forming part of said first generally radial passage.

7. The combination according to claim 1, in which the bottom of the bowl has a hollow nave extending into the bowl and receiving one end portion of the spindle, said first generally radial passage including generally radial holes in the spindle and nave, said passage forming means including a hollow member defining a second chamber surrounding the nave in the bowl, said central passage extending upward in the spindle above said holes and opening into the central portion of the second chamber, the hollow member having an opening in its outer peripheral portion, said opening and second chamber each forming part of said second generally radial passage means, the hollow member having a bottom surrounding the nave above said holes and defining with the bowl bottom a generally radial channel into which said holes open, said channel forming part of said first generally radial passage.

8. The combination according to claim 1, in which the spindle has an enlarged hollow flange at one end, said tube projecting into the interior of the flange, said sealed

flow connections including an outer sealing ring pressed against said flange, a sealing collar on the tube within said flange and having generally radial spokes extending outward to the flange, and an inner sealing ring pressed against said collar, said rings, flange and collar forming concentric passages interconnecting the spindle passages with said stationary inlets, respectively.

9. The combination according to claim 1, comprising also a set of conical discs in the separating chamber, said passage forming means constituting a carrier for the discs.

10. The combination according to claim 1, comprising also a set of conical discs in the separating chamber, said passage forming means including a hollow member supporting the discs and defining a second chamber in the bowl, said second chamber forming part of said second generally radial passage.

11. The combination according to claim 1, comprising also a set of conical discs in the separating chamber, said passage forming means including a hollow member supporting the discs and defining a second chamber in the bowl, said second chamber forming part of said second generally radial passage, the hollow member also defining with the bottom of the bowl a separate channel forming part of said first generally radial passage and leading into the separating chamber around the outer edge of the bottom disc in said set.
